(57) CLAIM

The ornamental design for mouse with wide cross band, as shown and described.

DESCRIPTION

FIG. 1 is a perspective view of a mouse with wide cross band showing our new design;

FIG. 2 is a top plan view thereof;

FIG. 3 is a right side elevational view, the left side elevational view being a mirror image thereof;

FIG. 4 is a bottom plan view thereof;

FIG. 5 is a front elevational view thereof; and,

FIG. 6 is a rear elevational view thereof.
